(57) **CLAIM**

The ornamental design for a motion assisting device, as shown and described.

DESCRIPTION

FIG. 1 is a front elevational view of a motion assisting device showing our new design.

FIG. 2 is a rear elevational view thereof.

FIG. 3 is a top plan view thereof.

FIG. 4 is a bottom plan view thereof.

FIG. 5 is a right side elevational view thereof, the left side elevational view being a mirror image of the right side elevational view shown; and,

FIG. 6 is another front elevational view thereof showing a use state.

The outline of the partial human body shown in broken lines shown in FIG. 6 is for the purpose of illustrating an environment of use of the motion assisting device and forms no part of the claimed design. The remaining broken lines
